UNITED STATES PATENT OFFICE.

CHARLES H. COURT, OF JERSEY CITY, NEW JERSEY, ASSIGNOR OF ONE-HALF OF HIS RIGHT TO JOHN C. HARING, OF SAME PLACE.

DESIGN FOR PENCIL-CASES.

SPECIFICATION forming part of Design No. 11,693, dated March 23, 1880.

Application filed February 7, 1880. Term of patent 7 years.

To all whom it may concern:

Be it known that I, CHARLES H. COURT, a citizen of the United States, residing at Jersey City, in the county of Hudson and State of New Jersey, have invented and produced a new and original Design for Pencil-Cases, of which the following is a specification, reference being had to the accompanying drawings, making part thereof.

10 Figure 1 is a side view of my newly-designed pencil-case, and Fig. 2 is an edge view of the same, these two views being deemed necessary to fully illustrate my design.

This design relates to the ornamental case or inclosure for a pencil; and said case consists of a scalloped and corrugated figure representing a shell, from which protrudes a pencil having a ring on one end, which may be attached to a watch-chain or necklace.

20 In the annexed drawings, A designates the case of a pencil, which case is made to imitate a pearl oyster-shell, having scallops b and ra-

dial corrugations a and wings or flanges c c. In cross-section the shell or case A is convex, and in a front view it is of a circular form. 25 The upper portion, B, of the pencil is cylindrical and protrudes from what represents the winged or hinged part c c of the shell, having a ring, D, on its extremity. The lower portion, B', of the pencil, which represents the 30 nib, protrudes from the scalloped edge a of the shell.

A tooth-pick or watch-key bit may be substituted for pencil-nib B'.

I claim—

35 The design for a pencil-case herein shown and described, the same consisting of the shell A, having a scalloped edge, b, and a convex corrugated surface, a, in combination with the pencil B B', having a ring, D, as shown.

CHARLES H. COURT.
